UNITED STATES PATENT OFFICE.

CHARLES CLAY TERHUNE, OF PLATTE, SOUTH DAKOTA.

TELEPHONE-TRANSMITTER.

1,125,764.

Specification of Letters Patent. Patented Jan. 19, 1915.

Application filed October 23, 1913. Serial No. 796,911.

To all whom it may concern:

Be it known that I, CHARLES CLAY TERHUNE, a citizen of the United States, residing at Platte, in the county of Charles Mix 5 and State of South Dakota, have invented certain new and useful Improvements in Telephone-Transmitters; and I do hereby declare the following to be a full, clear, and exact description of the invention, such as 10 will enable others skilled in the art to which it appertains to make and use the same.

This invention relates to telephone transmitters, and more particularly to a permanent magnet attachment adapted to be secured to telephones of standard types having iron diaphragm.

The principal object of the invention is the provision of a permanent magnet in connection with the diaphragm of a transmitter, 20 whereby the sound waves actuating the diaphragm are assisted by the action of the magnet, in compressing the granular carbon of the transmitter, the magnet also exerting a tension on the diaphragm thereby preventing eddy vibrations and side tones, and for this reason the attachment may be found 25 of great advantage when used with a telephone transmitter of factories or other noisy places.

Another object of this invention is to provide a device of the class described, which will be simple, durable, efficient in operation and inexpensive to manufacture.

With these and other objects in view the 35 invention resides in the construction, combination, and arrangement of parts, herein-after more fully described and claimed and illustrated in the accompanying drawing, in which like characters of reference indicate like parts throughout the figures, of 40 which,

Figure 1 represents a perspective view of a telephone transmitter looking from the back of the same, the housing having been 45 removed, and showing the invention as applied thereto, Fig. 2 represents an end elevational view of the magnet, Fig. 3 represents a bottom plan view thereof, Fig. 4 represents a vertical, transverse sectional view 50 through a telephone transmitter showing the invention as applied thereto.

Referring more particularly to the drawing it will be seen that the invention which comprises a permanent magnet 5, has been 55 shown as secured by means of a clip 6 to the bridge 7 of an ordinary granular carbon,

iron diaphragm, a telephone transmitter, at one end of said bridge, said magnet being substantially semi circular in shape, and having at its outer ends a pair of lugs 8 which form the poles of the magnet and which extend inwardly toward the diaphragm 9, and which are spaced about one thirty second of an inch from said diaphragm. The magnet is flat on the top and bottom and the sides of the magnet converge 60 slightly downwardly from the bottom to the top of the magnet, and the clip has its ends bent as at 10 to lie against the bridge at one end thereof, said clip being secured by 65 means of screws 11 and 12, the former extending through one end portion 10 of the clip into the bridge, and the latter extending through the opposite end portion 14 of the clip, through the bridge near one end thereof and into the casing 13 of the transmitter. 70

Although I have described the magnet as being horse-shoe shaped, it will be understood that the shape and proportion of the magnet may be varied to conform with the 75 requirements of transmitters of different types, without departing from the spirit of the invention.

It will be seen by this construction that the ends of the magnet will tend to assist in 80 actuating the diaphragm in pressing the granular carbon 14 and will tend to prevent any vibrations and side tones by the diaphragm, and it has been found by experiment that the magnet may be used to good 85 advantage for local or long distance work.

Although I have described the preferred embodiment of my invention, I may desire to make such changes in the construction, combination, and arrangement of parts 90 thereof, as do not depart from the spirit of the invention and scope of the appended 95 claims.

Having thus described my invention, what I claim as new and desire to secure by Letters-Patent is:

1. The combination with a granular carbon transmitter having an iron diaphragm, of a bridge spaced from said diaphragm, an arch formed intermediate the ends of said bridge, a permanent magnet partially inclosing said arch and a clip arching over said magnet clamping it to said bridge and to the casing of the transmitter. 105

2. In a combination with a granular carbon transmitter having an iron diaphragm, a bridge spaced from said diaphragm, an 110

arch formed integral with said bridge, a permanent magnet partially inclosing said arch and a clip embracing said magnet clamping it to said bridge and to the casing 5 of the transmitter.

3. In combination with a granular carbon transmpter having an iron diaphragm, a bridge spaced from said diaphragm, an arch formed integral with said bridge to 10 permit of the positioning of said granular carbon therein, a permanent magnet partially inclosing said arch and said granular carbon, and means for securing said magnet to the bridge and to the casing of the transmitter.

4. In combination with a granular carbon transmitter having an iron diaphragm, of a permanent magnet, of a transmitter bridge and of a clamp, said clamp being attached 15 at one end to said bridge, arching over said

magnet, clamping it to said bridge, and to the casing of a transmitter.

5. The combination with a granular carbon transmitter, having an iron diaphragm of a bridge to said transmitter, an arch 25 formed integral with said bridge to permit of the positioning of the granular carbon therein, a permanent magnet partially inclosing said arch and said granular carbon, and a clip arching over said magnet clamp- 30 ing it to said bridge and to the casing of the transmitter.

In testimony whereof I have signed my name to this specification in the presence of two subscribing witnesses.

CHAS. CLAY TERHUNE.
